UNITED STATES PATENT OFFICE.

ERNEST LESLIE RANSOME, OF NEW YORK, N. Y.

MIXING-MACHINE.

SPECIFICATION forming part of Letters Patent No. 770,477, dated September 20, 1904.

Application filed April 1, 1902. Serial No. 100,939. (No model.)

To all whom it may concern:

Be it known that I, ERNEST LESLIE RANSOME, a citizen of the United States, residing at Greater New York, in the State of New York, 5 have invented Improvements in Mixing-Machines; and I hereby declare the following to be a description thereof.

My improvements relate to mixing-machines.

10 The objects of my improvements are to make a mixing-machine that will mix more thoroughly than the present continuous mixers now in use and that will avoid the locking and binding so common in such mixers.

15 My improvements consist, first, in the provision of means by which one or more helical bafflers are mounted within a revoluble hollow member, such as a drum or shaft, in a way to rotate therewith and to be withdrawn 20 easily therefrom and replaced with despatch; secondly, in the provision of means for maintaining a space between the revoluble member and one or more bafflers in order to prevent the lodgment or accumulation of material and to insure the operation of the bafflers without binding or locking the material undergoing treatment against any part of the machine; thirdly, to provide an improved 25 construction of bafflers which operates in an efficient manner to quickly and thoroughly mix the materials, and, finally, in the construction and arrangement of parts which will be defined by the annexed claims.

Figure 1 is a revolving hollow shaft or drum 30 with the head K. It is partly in section showing two helical bafflers of the same diameter placed inside. Fig. 2 is a cross-section of the drum and bafflers of Fig. 1, the plane of the section being indicated by the dotted line X 35 X, said view looking toward the head K. Fig. 3 is a cross-section on the line S S of Fig. 4, also looking toward the head K and showing a preferred form of bafflers within a revoluble hollow member, such as a drum, 40 shaft, or cylinder. Fig. 4 is a longitudinal sectional elevation of a mixer of the type shown by Fig. 3, illustrating a preferred arrangement of two helical bafflers within a revoluble hollow member. Fig. 5 is a plan

view of the mixer, with the revoluble hollow 50 member partly broken away and in section, said view showing one means for revolubly mounting and rotating said member. Fig. 6 is an elevation looking at the charging or inlet end of the machine. 55

Similar letters refer to similar parts in every figure.

My invention is as follows.

Within the revolving shell A, I place a plurality of helical bafflers B, each of said bafflers being of normal pitch, as shown by Fig. 1. In many cases one is sufficient; but in drums of large diameter it is often advantageous to use two or more bafflers of equal size and of normal pitch, as indicated at B C, 60 65 as shown in Fig. 1, for by so doing the capacity of the machine is increased without detriment to the quality of the mixing.

A preferred form or construction of the invention consists in placing within the larger 70 baffle D, Fig. 4, another one of smaller diameter, E, and by preference the smaller one has a greater pitch than the outer and larger one. The object of this arrangement is to attain a more thorough admixture, for the baffle E, conveying the material quicker than the baffle D, will cause a constant commingling of the materials in the two lines of travel, and to attain this end more fully by 75 preference I make one or both bafflers of irregular pitch and place them so that at points equidistant from the end of the mixer where the pitch is greater in the one it is normal or less than normal in the corresponding part of the other, so that where the pitch is less in 80 the outer baffle the material in its passage will so pile up that a greater portion thereof than usual will come under the influence of the inner baffle of greater relative pitch at that point and will be carried forward to intermix with the material farther ahead on the lower line of travel, and vice versa. Where the pitch of the inner baffle is less at that point, the outer baffle will receive within its sphere of action more of the material from 85 90 the inner line of travel.

In Fig. 1 of the drawings I have shown a plurality of bafflers B C within the revolving

drum, said bafflers being of equal diameters and intertwined one with the other. Fig. 4 of the drawings shows a plurality of bafflers D E, the latter, E, being of smaller diameter than the former, D, and arranged within the same. It is evident to those skilled in the art that instead of using a single baffle D or E in the construction of Fig. 4 I may use a plurality of intertwined bafflers of uniform diameter, similar to the bafflers B C of Fig. 1; but as such duplication of the bafflers D or E is an obvious expedient I have not considered it necessary to illustrate the same by the drawings.

15 In Figs. 5 and 6 of the drawings I have represented one embodiment of means for mounting and driving the drum which constitutes the hollow revoluble member. The drum A is shown as being provided with circumferential track-bands *a*, with which engage a plurality of bearing-rollers *a'*, the latter being journaled in suitable bearings *b*, which are supported by a suitable horizontal base or frame B'. This revoluble member A is also provided with an external gear C', the same having intermeshing engagement with a driving gear-pinion *c*, which is carried by a horizontal shaft D', the latter being journaled in suitable bearings *d*, provided on said base or frame. This shaft D' is adapted to be rotated by any suitable means, and the motion of the gear *c* is communicated to the gear C' for the purpose of rotating the drum A, the latter being supported by the rollers *a'*, so as to turn easily and freely on the base or frame B'.

In order to prevent the material from caking up or lodging within the angle formed between the baffle or bafflers and the shell of the drum or hollow shaft, I prefer leaving a space at that point, as shown at F. For the purpose of convenience in cleaning and repairs I prefer to have the baffle or bafflers so constructed that they can be bodily and easily withdrawn through the open delivery end of the drum or shell. This I accomplish by attaching the baffle or bafflers to the bars G, of which there are two or more. One or more of these are in turn engaged by the bar or bars H, which are rigidly attached to the shell of the cylinder and by which the baffle or bafflers are fixed in relation thereto. When the drum or hollow shaft is in motion, the action of the material mixing will cause the baffle or bafflers to thrust against the head K of the drum A, which will keep it or them from further independent movement; but in cases where there is no head the bars G and H can be bolted together, as at R, to prevent this movement, or other of any of the well-known devices may be used to attain this end.

The head K of the mixer shown by Figs. 1 and 2 is attached in a suitable way to the re-

ceiving or charging end portion of the revoluble member. This head is provided with a central opening *k*, which is shown in elevation by Figs. 2 and 6 and in section by Fig. 5, said opening *k* being of less diameter than the baffle or bafflers in order that the material may be supplied to the revoluble member. The head may furnish an abutment for the baffle to restrain it from endwise displacement in one direction within the revoluble member.

75 The head K in the construction shown by Figs. 3 and 4 has an opening *k'* of less diameter than the smaller internal baffle E. (See Figs. 3, 5, and 6.) The material is adapted to be charged into the drum through this opening in the mixer. The head K in this form of construction affords an abutment for both the bafflers D E to restrain them against endwise movement in one direction.

80 From the foregoing description, taken in connection with Figs. 1, 4, 5, and 6 of the drawings, it will be seen that the hollow revoluble member or drum A is provided at its receiving or charging end with a head having an opening, while the other end of the drum 85 is open for the free delivery of the material which is mixed by the operation of the bafflers and the rotation of the drum or member. The baffle or bafflers extend continuously throughout the hollow member or drum, so 90 that the machine will serve as a continuous mixer, the material being received through the head K of the drum and discharged through the other open end thereof.

95 The baffle or bafflers in the mixing-machine of my invention are not attached permanently to the drum or hollow member nor to one another, but the connection between the part or parts is afforded by longitudinally-disposed bars, which are arranged to insure 100 the rotation of the baffle or bafflers with the drum and which also permit the baffle or bafflers to be withdrawn endwise from said drum through the open delivery end thereof.

105 In the construction shown by Figs. 1 and 2 the drum is provided on its inside with longitudinal bars H, while the bafflers B C are furnished with complementary longitudinal bars G, the latter being disposed in lateral abutting engagement with the bars H. On 110 the rotation of the drum or member the bars H engage with the bars G to insure rotation of the bars G and bafflers B C with the member or drum A; but when the machine is at rest the bafflers B C and the bars H may be 115 withdrawn endwise from the drum without disconnecting the latter from its supporting devices, such as the rollers *a'*, on the frame or base.

120 The construction of parts shown by Figs. 3 and 4 is similar to the devices of Figs. 1 and 2, except that the inner baffle E is connected by longitudinal bars L to the larger baffle 125

D, the latter being provided with longitudinal bars G, which are disposed for engagement with similar bars H, which are fastened to the inside of the drum or member A. This 5 construction permits the baffle E to be withdrawn endwise from the drum and the baffle B, and, if desired, said baffle B may also be removed from the drum, the bars G sliding lengthwise of the bars H. The bolts R are 10 only used in cases of emergency and when the hollow member or drum A is not provided with a head, as K.

The inner baffle or baffles E by preference are rigidly attached to the outer baffle 15 or baffles at two or more points, as shown at L, or by any convenient means. For the purpose of mixing such material as mortar, &c., I prefer to break the baffles or puncture them with holes, as at M, Fig. 1. 20 I do not limit my invention to cylindrical drums, for the periphery of the drum or shaft may be many sided and of any convenient shape and the helical baffles may be shaped to more or less conform thereto; nor do I confine my invention to mixing-mills, for the use 25 of these helical baffles, in combination with a hollow revolving shaft, makes an excellent conveyer for broken stone and such like materials.

30 What I claim, and desire to secure by Letters Patent, is—

1. A machine of the class described, having an imperforate revoluble member open at one 35 end, a baffle within said member and unattached thereto, and coöperating devices on said member and the baffle for insuring the rotation of the latter with the former, said baffle being withdrawable endwise through the open end of the member. 40 2. A machine of the class described, having a revoluble imperforate member open at one end, a baffle within said member and unattached thereto, and bars fixed to the baffle and the member respectively, said bars of the 45 baffle having slidable engagement with the bars of the member on the endwise movement of the baffle, and also insuring the rotation of said baffle with said member.

3. A machine of the class described, having 50 a revoluble hollow member, a baffle therein, and coöperating bars on the member and baffle to make the latter rotate with the member and to permit the baffle to be inserted or withdrawn endwise.

55 4. A machine of the class described, having a revoluble imperforate hollow member, and a plurality of baffles each having flights of irregular pitch and mounted within said member, one baffle having a flight of one pitch disposed in coöperative relation to a flight of a dissimilar pitch of the companion baffle.

60 5. A machine of the class described, having a revoluble imperforate hollow member, and a plurality of baffles each having flights of

irregular pitch disposed in coöperative relation to one another and all mounted within said hollow member for rotation therewith. 65

6. A machine of the class described, having a hollow imperforate revoluble member, and a plurality of baffles each having flights of 70 unequal pitch; said baffles being of varying diameter and disposed for a baffle of small diameter to lie within a baffle of greater diameter, said baffles being arranged for their flights of unequal pitch to have coöperative 75 relation, and all of said baffles being mounted within said drum.

7. A machine of the class described, having a hollow imperforate member, and a plurality of baffles disposed within said member, the 80 baffle of greatest diameter being fitted to the drum for rotation therewith, and the baffle of less diameter being mounted within said larger baffle, the pitch of each baffle being 85 irregular.

8. A machine of the class described, having a hollow imperforate revoluble member, and a plurality of helical baffles each having flights of irregular pitch and mounted within 90 said member, said baffles being relatively arranged for a portion of increased pitch on one baffle to lie adjacent to a portion of less pitch on the companion baffle.

9. A machine of the class described, having a hollow revoluble member, and helical baffles of different diameters disposed within 95 said member and within one another, the pitch of the large baffle varying in reverse ratio to the variations of pitch of the smaller baffle.

10. A machine of the class described, having 100 a hollow revoluble member, a continuous helical baffle within said member, longitudinal bars attached to said baffle and to the member respectively, and having lateral abutting engagement and adapted to slide one on the 105 other, said bars being effective in insuring rotation of the baffle with said member and to relatively space said parts to produce an annular clearance-space between the inner surface of the member and the edge of the helical baffle. 110

11. A machine of the class described, having a hollow imperforate member, a continuous helical baffle having flights of irregular pitch mounted within said member and spaced relatively thereto, and another continuous helical baffle also having flights of irregular pitch and disposed within the first-named baffle for the flights of the two baffles to lie in coöperative relation. 115

12. A machine of the class described, having a revoluble imperforate member, a helical baffle having flights of irregular pitch and disposed in said member for rotation therewith, and another baffle also having flights 125 of irregular pitch and superposed upon and athwart the first-named baffle.

13. A machine of the class described, having

a revolute hollow member, a helical continuous baffle disposed in and revolute with said member, and another baffle superposed upon and athwart the first-named continuous baf-
5 fler.

14. A machine of the class described, having a hollow revolute member, a helical baffle attached within said member, and a head fast

with the member and having a normally unobstructed charging-opening of less diameter than the baffle, said head affording an abutment for the baffle.
